(57) **CLAIM**

The ornamental design for a flashlight as shown and described.

DESCRIPTION

FIG. 1 is a front, top perspective view of a flashlight, showing our new design;

FIG. 2 is a front, bottom perspective view thereof;

FIG. 3 is a rear, top perspective view thereof;

FIG. 4 is a top view thereof;

FIG. 5 is a bottom view thereof;

FIG. 6 is a left side view thereof;

FIG. 7 is a right side view thereof;

FIG. 8 is a front view thereof;

FIG. 9 is a rear view thereof;

FIG. 10 is a front, top perspective view thereof in a position of use with the cap separated from the main body of the flashlight; and,

FIG. 11 is a rear, top perspective view thereof in a position of use with the cap separated from the main body of the flashlight and the charging port open.

The broken lines depict portions of the flashlight that form no part of the claimed design.

1 Claim, 7 Drawing Sheets
